UNITED STATES PATENT OFFICE.

ALBERT J. HORTON, OF WHITE PLAINS, NEW YORK, ASSIGNOR TO THE CUTLER-HAMMER MFG. CO., OF MILWAUKEE, WISCONSIN, A CORPORATION OF WISCONSIN.

MOTOR CONTROLLER.

Application filed October 15, 1920. Serial No. 417,102.

To all whom it may concern:

Be it known that I, ALBERT J. HORTON, a citizen of the United States, residing at White Plains, in the county of Westchester and State of New York, have invented new and useful Improvements in Motor Controllers, of which the following is a full, clear, concise, and exact description, reference being had to the accompanying drawing, 10 forming a part of this specification.

This invention relates to motor controllers.

Heretofore it has been proposed to employ for motor starting and speed regulation a rheostat to initially include in the motor circuit a given amount of armature resistance and a counter-voltage switch or other switch responsive, subject to control by the motor speed, to exclude such resistance to varying degrees according to the previous setting of said rheostat. However, as heretofore designed, such controllers have not been entirely satisfactory owing to the difficulty of securing the desired slow speed adjustments under different load conditions and at the same time securing certainty of starting.

The present invention has among its objects to provide a controller of the aforesaid character wherein this difficulty is overcome.

Other objects and advantages of the invention will hereinafter appear.

The accompanying drawing diagrammatically illustrates one embodiment of the invention which will now be described, it being understood that the invention is susceptible of various modifications without departing from the scope of the appended 40 claims.

Referring to the drawing, the same illustrates a controller affording both armature and field regulation of a shunt motor 1. This motor is shown as comprising an armature a and a shunt field winding f .

The controller comprises a rheostat 2 having an armature resistance r and a field resistance r' , a counter-voltage switch 3 for controlling said armature resistance and a relay 4 for controlling said field resistance.

The rheostat comprises a pivoted arm 5, a series of contact buttons 6 connected to the

resistance r and arranged to be progressively engaged by one end of said arm, segments 7 and 8 to be engaged by the same end 55 of said arm, a series of contacts 9 connected to the field resistance r' and arranged to be engaged by the opposite end of arm 5 and segments 10, 11 and 12 arranged to be engaged by the latter end of said arm. The 60 arm 5 has a line connection extending to the hub thereof; and the portion of said arm engageable with the contact buttons 6 and segments 7 and 8 is insulated from the remainder of said arm.

The arrangement of contact and segments and the circuit connections are such that when the arm 5 is in the position illustrated a circuit extends from line L through the winding of relay 4 by conductor 13 to and 70 through arm 5 to segment 11 by conductor 14 to the resistance r at an intermediate point and thence through a portion of said resistance by conductor 15 to and through the motor armature by conductor 16 to line 75 L'. Thus provision is made for inclusion of two steps of resistance in series with the motor armature for starting. Moreover, the arrangement is such that with the arm 5 in engagement with either the uppermost 80 contact 6 or the segment 7 the same amount of resistance r would be included in the armature circuit but subject to exclusion as a whole or in part upon response of the switch 3 which completes circuit from line L 85 through a portion of the winding of relay 4 by conductor 17 to segment 8 and thence to conductor 15 either directly or through one step of resistance r according to the setting of the arm 5.

On the other hand the arrangement is such that the arm 5 may be moved counter clockwise to include either one or two additional steps of resistance r for restriction of the running speed of the motor under light 95 load conditions, circuit then being traceable from arm 5 to segment 12 by conductor 18 to segment 8 and thence through the insulated section of the arm 5 to one or the other of the lowermost resistance contacts 6 for normal inclusion of the additional resistance. Under such conditions response of the countervoltage switch merely parallels the circuit to segment 8 thus being without effect.

upon the amount of resistance included in the motor circuit. Should the additional resistance prevent starting of the motor, it is merely necessary to temporarily return 5 the arm 5 to the position illustrated whereupon the starting resistance is reduced to two steps.

In all of the above-described positions of the arm 5 said arm engages segment 10 10 whereby the field circuit is completed exclusive of all of the resistance r^1 . This circuit may be traced from the arm 5 to segment 10 by conductors 19 and 20 to and through the field winding by conductors 15 21 and 16 in Line L¹. Moreover, should the arm be initially set to include any portion of the resistance r^1 , such resistance would normally be short-circuited by the relay 4. This relay is normally open but 20 its winding 4 which comprises two cumulative sections connected in series with the motor armature effects closure thereof immediately upon closure of the armature circuit and throughout the starting period. 25 When, however, the counter-voltage switch 3 responds, it short-circuits one section of the winding of switch 4 whereby said switch is permitted to open to include the selected amount of field resistance when the armature current is reduced to a given value.

Thus the controller provides for inclusion of at least a given amount of armature resistance and inclusion of all field resistance for starting while providing for reduction 35 of the armature resistance and inclusion of the field resistance automatically upon proper acceleration of the motor and moreover provides for increasing the amount of armature resistance for speed reduction 40 without interference with the automatic operation.

As above set forth, if the motor fails to start with the additional armature resistance included in circuit the arm may be temporarily placed in the position illustrated 45 and thereafter moved to include the desired additional resistance.

What I claim as new and desire to secure by Letters Patent is:

50 1. In a motor controller, in combination, a starting resistance for the motor circuit means operable automatically for excluding said resistance, means to be set to maintain in circuit a variable amount of said resistance and an additional resistance to be also included by said last-mentioned means at will.

60 2. In a motor controller, in combination, an automatically responsive instrumentality, and a rheostat having resistance for the motor circuit to be excluded by said instrumentality, such resistance being included in the motor circuit for starting regardless of the setting of said rheostat and being subject to exclusion by said instrumentality in

varying amounts according to the setting of said rheostat, said rheostat having additional resistance to be included in circuit with the motor at will.

65 3. In a motor controller, in combination, 70 an armature rheostat, a switch responsive automatically to shunt a part of the resistance of said rheostat, and circuit connections insuring inclusion in the motor circuit of at least a given amount of the resistance of 75 said rheostat prior to response of said switch and providing for inclusion in the motor circuit of additional resistance of said rheostat at will.

4. In a motor controller, in combination, a 80 rheostat, an associated switch having means for operating the same automatically subject to a delay, circuit connections insuring inclusion in the motor circuit of at least a given amount of the resistance of said rheostat to be excluded by said switch in varying amounts according to the setting of said rheostat and circuit connections for including in the motor circuit additional resistance of said rheostat according to adjustment of 90 the latter.

5. In combination an electric motor, a 95 rheostat connected to said motor for inclusion in circuit with the latter of a given amount of the resistance of said rheostat regardless of the setting of the latter, said rheostat having additional resistance for inclusion in the motor circuit at will and a switch having means to operate the same automatically but subject to a delay to exclude 100 to varying degrees the first-mentioned portion of said resistance according to the adjustment of said rheostat.

105 6. In a motor controller, in combination, an automatically responsive instrumentality, a rheostat having resistance to be included in the motor circuit subject to control by said instrumentality, said rheostat having contacts to vary the amount of resistance thereof included in the motor circuit, 110 certain of such contacts being dependent upon response of said instrumentality for connection thereof in circuit, said rheostat also having other contacts engaged and disengaged according to the setting of the former contacts, the latter contacts controlling a circuit providing for inclusion of at least a given amount of resistance in the motor circuit prior to response of said means and connections whereby disengagement of said 115 latter contacts permits setting of the former contacts to include in the motor circuit a greater amount of said resistance.

120 7. In a motor controller, in combination, an automatically responsive instrumentality, 125 and a rheostat having line and motor connections, certain of which are controlled by said instrumentality, said rheostat comprising resistance contacts, a contact arm having insulated sections one of which co-oper- 130

ates with said contacts to include a variable amount of the rheostat resistance in the motor circuit and a contact engaged by the other section of said arm to make and break a connection to the resistance at an intermediate point for insuring inclusion of at least a given resistance subject to exclusion there- of by said instrumentality in varying amounts according to the setting of said arm and for enabling inclusion of additional 10 resistance at will by adjustment of said arm.

In witness whereof, I have hereunto subscribed my name,

ALBERT J. HORTON.
